UNITED STATES PATENT OFFICE.

FREDERICK LIONEL WOOD, OF DENVER, COLORADO.

WALL DIRECTORY.

Application filed June 25, 1923. Serial No. 647,643.

To all whom it may concern:

Be it known that I, FREDERICK L. Wood, a citizen of the United States, residing at Denver, in the county of Denver and State 5 of Colorado, have invented certain new and useful Improvements in Wall Directories, of which the following is a specification.

My invention relates to wall directories for clubs, office buildings and other institutions requiring a convenient method of displaying the names of their members, tenants or inhabitants, and its primary object is to provide a directory of the above described character so constructed that any 10 one of a plurality of name plates arranged upon its front in alphabetical order, are readily inserted, removed or interchanged without disturbing the others.

A further object of the invention is to 20 provide each name plate individually with a protective cover which prevents of its being soiled by dust or dirt, and still other objects reside in features of construction and a novel arrangement of parts all of which 25 will fully appear in the course of the following description.

A practical embodiment of my invention has been illustrated in the accompanying 30 drawings in the several views of which like parts are similarly designated and in which—

Figure 1 represents a face view of my improved wall directory;

Figure 2, a vertical section along the line 35 2—2, Figure 1;

Figure 3, a horizontal section taken on the line 3—3, Figure 1;

Figure 4, a fragmentary magnified section 40 taken on a plane similar to that of Figure 2;

Figure 5, an enlarged face view of one of the removable panels comprised in the construction, separate from the frame in which it is normally supported;

Figure 6, a longitudinal section along the line 45 6—6, Figure 5;

Figure 7, an enlarged transverse section of the panel taken on the line 7—7, Figure 5;

Figure 8, a fragmentary sectional view 50 similar to Figure 6, showing a name plate in place on the panel, and drawn to an exaggerated scale;

Figure 9, an enlarged and fragmentary 55 perspective view of one of the name plates and its protective envelope;

Figure 10, a similar view of the envelope without the name plate; and

Figure 11, an enlarged fragmentary section taken on the line 11—11, Figure 1. 60

Referring more specifically to the drawings, my improved wall directory comprises a frame 5 of ornamental appearance, which is adapted to be suspended or otherwise fastened in an upright position against a 65 wall surface of a hall, room or other part of the building.

The frame has in its front a plurality of vertical recesses 6 divided from each other by vertical partitions 7 and extended at their 70 ends into the solid upper and lower marginal part of the frame as indicated at 6^a and 6^b in Figures 2 and 4.

The pockets thus produced are at the upper ends of the recesses deeper than at the 75 lower ends of the same, to permit of the panels which normally occupy the recesses as will hereinafter be described, being removed therefrom by first lifting them upwardly out of the lower pockets and then moving them forwardly and downwardly from the upper pockets.

The back 8 of the frame has in each of its recesses a longitudinal opening 8^a which 80 lightens the construction and promotes an 85 even contact of the respective panels with the back, and the frame has above its recessed portion, a smooth surface 6^d to receive the name of the club, building or other institution in which the directory is used. 90

The panels of the directory hereinbefore referred to, each consist of an oblong rectangular body 9 preferably composed of two sections 9^a and 9^c of different kinds of wood, fastened one upon the other as best shown 95 in Figures 6 and 7 of the drawings.

The body of each panel is longitudinally 100 grooved at its rear side at which it engages with the back of the frame in which they are supported, and it is provided at its front with a plurality of parallel open-ended and open-faced, transversely extending pockets 10 to receive the name plates hereinafter to be described.

The pockets are divided from each other by transverse partitions 12 which are longitudinally grooved to provide slideways for the name plates, and the panel has at its lower end, a knob 13 to facilitate its removal 110 from the recess of the frame in which it is normally supported.

The width of the panels corresponds with

that of the recesses in the frame, and their length is such that when supported upon the bottom of the respective recesses as shown in Figure 4, enough space is left at the upper end of the recesses to lift the panels for their removal from the frame as hereinbefore explained.

The name plates 14 which in practice are inserted in the pockets of the panels, are 10 contained in sheaths or envelopes 15 of celluloid or other transparent material which are formed to fit snugly inside the pockets as best shown in Figure 8.

The envelopes are made of rectangular 15 pieces of the desired material, the longitudinal edge-portions of which are bent upon and in spaced relation to the body portion of the same to form retaining flanges 15^a for the name plates which ordinarily are made 20 of strips of heavy paper upon which the names are printed or otherwise affixed.

The name plates correspond in length with the protective envelopes in which they are enclosed; they fit snugly between the flanges 25 of the envelopes and they are readily inserted or removed from the envelopes by sliding them through the open ends thereof. The envelopes are in like manner, inserted in the pockets of the panels with their flanged 30 sides innermost, and the panels are placed in the recesses of the supporting frame as hereinbefore described.

The partitions between the recesses, and one 35 of the upright marginal portions of the frame at one side of the same, are provided with equidistant holes 16 placed in alignment with the name plates on the panels and adapted for the insertion of pegs 17 used 40 to indicate the presence or absence of the persons whose names appear on the directory.

Having thus described my improved wall 45 directory, it will be apparent that any of the name plates comprised therein, are readily changed without disturbing the arrangement of the others; that the name plates are adequately protected from being soiled by dust or dirt without the expensive and cum-

bersome panes of glass found in other directories of similar type; that the names can 50 be arranged without removing or adjusting any part of the supporting frame, and that the entire construction is free from locks, hooks or other fastening devices.

The construction of the panels of two different kinds of wood prevents warping and the longitudinal ribs at the back thereof, engaging with the slotted surface at the back of the recesses in the supporting frame, provide for an even contact of the parts and 60 strengthen and lighten the construction.

Having thus described my invention, what I claim and desire to secure by Letters Patent is:

1. A wall directory comprising a frame 65 having in its front, a recess extended into pockets formed in the upper and lower marginal portions of the frame, a panel fitted in said recess to move longitudinally between the sides thereof, and normally supported in 70 the lower pocket, the panel having in its face a plurality of transverse slideways, and name plates in the slideways, the upper pocket of the recess being deeper than the lower pocket to permit of clearing the lower edge 75 of the panel by upward movement thereof for the removal of the panel from the frame in a forwardly tilted position.

2. In a wall directory, the combination 80 with a recessed frame, of a panel having a longitudinally grooved side engaging with a surface of the recess, and having in its opposite side, a plurality of transverse pockets, and name plates in said pockets.

3. A wall directory comprising in combination, a frame having a recess, a panel in 85 said recess having upon its face, a plurality of transverse partitions which are grooved to provide open-ended slideways, and name plates movable in said slideways, the panel fitting between the sides of the recess to 90 close the ends of the slideways when in place therein.

In testimony whereof I have affixed my signature.

FREDERICK LIONEL WOOD.
